UNITED STATES PATENT OFFICE

102,322

DESIGN FOR A CIRCULATING FAN

Ernest A. Camp and Paul J. Camp,
Weatherford, Tex.

Application October 10, 1936, Serial No. 65,250

Term of patent 7 years

To all whom it may concern:

Be it known that we, Ernest A. Camp and Paul J. Camp, citizens of the United States, and residents of Weatherford, in the county of Parker and State of Texas, have invented a new, original, and ornamental Design for a Circulating Fan, of which the following is a specification, reference being had to the accompanying drawing, forming a part hereof.

In the drawing the figure is a perspective view of a circulating fan showing our new design.

We claim:

The ornamental design for a circulating fan, as shown.

ERNEST A. CAMP.
PAUL J. CAMP.
